UNITED STATES PATENT OFFICE.

BEDELL PARKER AND ROWLAND W. SPAIN, OF NEW YORK, N. Y.; SAID SPAIN
ASSIGNOR TO SAID PARKER.

UNION UNDERGARMENT.

1,184,120.

Specification of Letters Patent.

Patented May 23, 1916.

Application filed August 18, 1913. Serial No. 785,341.

To all whom it may concern:

Be it known that we, BEDELL PARKER and ROWLAND W. SPAIN, citizens of the United States, residing at New York, county of New York, and State of New York, have invented certain new and useful Improvements in Union Undergarments, of which the following is a specification.

This invention relates to union undergarments.

A desideratum in a union undergarment is a normally closed crotch which can, however, be readily opened.

Heretofore it has been proposed to propose a crotch having a flap which may be opened but the crotch itself is, in reality, an open crotch. Generally speaking, so-called closed crotches which have flaps are subject to several disadvantages, among which are difficulty in keeping the crotch normally closed and necessitating the use of buttons which cause discomfort to the wearer, liability of the edges of the flap to curl and form ridges which are uncomfortable, and catching in the tails of the outer shirt of the wearer.

Our invention dispenses with any flap or flaps at the crotch of the garment and thereby obviates all discomforts and disadvantages incident to a flap crotch, but at the same time provides a flap construction for the undergarment and affords means whereby the seat of the undergarment may be naturally and quickly opened or closed.

Our invention, as distinguished from prior so-called closed crotch union undergarments which have a flap in the crotch, has a crotch which is permanent, devoid of flaps or buttons, and is as comfortable as the usual underdrawers while having all of the advantages of an open crotch.

Our invention contemplates the provision of a union undergarment having a permanently closed crotch and a posterior leg portion constructed as one large complete flap having a detachable connection along the outer side of the leg portion, buttons and buttonholes being preferably provided, and, in addition, the back portion of the undergarment has a gore which is overlapped by the posterior leg portion aforesaid. The posterior leg portion aforesaid hinges or turns on a rear seat seam and the buttons or fasteners at the side of the leg portion are relatively low down so as to be conveniently

and naturally manipulated by the fingers of the wearer at that side of the garment and the entire posterior leg portion readily thrown back, affording the desired opening in the seat, when desired. Preferably, the posterior leg portion which constitutes the flap aforesaid has an oblique upper edge, devoid of buttons or fastenings of any kind and extends from a point at or near the waist line down to a buttoning or fastening point at a convenient height at the side of the leg.

In a uniform undergarment embodying our present invention, we may provide an elastic belt section at the back or have said belt extend completely around the garment, but we do not limit ourselves to the use of an elastic belt of any nature whatsoever as our invention is distinct and separate therefrom. A union undergarment provided with the present invention may have sleeves or be sleeveless. Preferably, it will be provided with a front open from the neck to the crotch thereof and having suitable fastening means such as buttons and buttonholes, as is common in union undergarments. We do not, however, limit ourselves to any construction other than the permanent crotch and posterior leg portion previously set forth.

A preferred embodiment of the invention is set forth hereinafter and is shown in the accompanying drawings, in which—

Figure 1 is a rear perspective showing the undergarment in use; Fig. 2, a rear elevation of the undergarment alone, the posterior leg portion being unbuttoned at its upper part ready to be completely unbuttoned to open the seat of the undergarment; and Fig. 3, a detail showing the permanent crotch, the leg portion being spread out.

The body 1 may be provided with sleeves or be sleeveless, the latter construction being illustrated. The front of the body extends the full length of the garment and includes the front leg portions 2. Preferably, the entire front of the undergarment from the neck to the crotch 3 is open and provided with suitable buttons and buttonholes, as usual in union undergarments. The legs and the body 1 may be directly joined at the rear or, a belt 4 of any suitable elastic textile material may be interposed and connected to the body and leg portions by seams 5, and 6. We do not limit our

selves to the provision of an elastic belt section 4, nor do we exclude such elastic belt section if we desire to employ it, but it constitutes no part of our invention.

5 The posterior leg sections are shown at 7 and 8, the former being permanent. One of the front leg sections 2 is joined by a permanent side seam at 9 to the permanent leg section 7. The posterior leg sections 7 and 10 8 have a permanent crotch 3. These leg sections being permanently joined by a seam 10 which, with the inner leg seams 11 and 12 and the short front seam 13 which is connected to the open front of the undergarment, constitute the closed crotch.

15 The entire posterior leg section 8 constitutes a flap which hinges on the seat seam 10. The upper part 14 of the leg section 8 is arranged obliquely, extending downwardly from the seam joint 15 which is disposed substantially at the waist line, to the point 16 at or near which there is provided a suitable fastening device, preferably a button and buttonhole, whereby the leg section 8 is connected to the front leg section 2 at the side. This juncture is preferably at a height about that of the hand of the wearer when hanging naturally at the side so that it is a natural movement to grasp 20 and unfasten the section 8 when desired. At a point lower down, preferably somewhat above the extreme lower edge of the leg, there is provided another fastener 17, preferably a button and buttonhole for joining the leg section 8 to the leg section 2. We do not limit ourselves to only two fasteners such as 16 and 17 nor to the exact 25 location shown in the drawings.

30 A gore 18 which is preferably free for a short distance at 19, is connected by seam 20 to the front leg section 2 and by seam 6 to the body 1, through the medium of the belt 4 or directly to the body 1 if such belt is not employed. The lower edge 21 of the 35 gore 18 is also preferably arranged obliquely or on the bias and extends from a point 22

in the seam 10 down to the lower edge of said gore 18. The disposition of the gore 18 underneath the posterior leg portion 8, prevents gapping of the garment at this 50 point and renders it comfortable. Consequently, when the leg section 8 is closed, there is no pulling apart of the lower edge 21 and the upper edge 14. Preferably, no button or fastening is employed to connect 55 the gore 18 and the leg section 8 together in order that there may be no possible discomfort to the back of the wearer, but we do not limit ourselves to the absence of a fastening between these parts.

60 It will be seen that the rear opening extends only partially across the back of the garment, that is, it originates in the back and extends only partially across the same instead of entirely across the back of the 65 garment. In the latter construction the transverse or crosswise-extending opening would be larger than the conditions called for and the flap covering such opening would be of such great length that in the 70 use of the garment the flap would tend to gap and open unnecessarily, thus rendering the garment objectionable in that respect.

Having thus described our invention, what we claim as new and desire to secure by Letters Patent, is:—

75 A union undergarment having a permanently closed crotch, an opening originating in its back and extending obliquely downwardly to the outside of only one of the legs 80 of said undergarment, and downwardly of said leg, thereby providing a seat flap, fastening means for said seat flap, and a gore arranged under the upper part of the seat flap.

85 In testimony whereof, we hereunto affix our signatures in presence of two witnesses.

BEDELL PARKER.
ROWLAND W. SPAIN.
